UNITED STATES PATENT OFFICE.

JOHN Q. SHERMAN, OF DAYTON, OHIO.

MANIFOLDING MACHINE.

Application filed September 23, 1921. Serial No. 502,697.

My invention relates to manifolding machines, particularly of the type wherein the paper is pulled out by hand from the machine itself and to aligning devices operable within holes in the plurality of forms being used, for bringing about a true alignment of all forms when being written upon.

In machines of the pull-out type it has been familiar practice in the past to provide one or more pins which lie in the path of the papers and can be permitted to rise up into holes formed in the paper for the purpose of aligning the various apertured webs.

15 The pins lie beneath the webs, and their operation cannot be observed, and, furthermore, where the pins are to be moved there must be mechanism for moving them, combined with resilient mechanism for forcing them in such a manner against the underside of the paper webs that when the holes come over them they will rise up into said holes and stop the paper movement.

20 In addition to this there must be mechanism for withdrawing the pins from the paper when it is to be fed along by hand.

The main object of my invention is to provide a mechanism wherein there are aligning pins which have a limited or "jogging" movement and means distinct from the pins for lifting the paper bodily therefrom and subsequently forcing it down on the pins when the holes in the paper permit this action to take place.

35 I also have as my object to strip the paper from the pins and hold it firmly while the operator obtains a grasp thereon, after which the operation of withdrawing the paper may be continued with the paper engaging or guiding plates in normal position and the resilient members resting on the surface of the paper.

40 These objects and other advantages to be noted, I accomplish by that certain construction and arrangement of parts to be hereinafter more specifically pointed out and claimed.

In the drawings,

Figure 1 is a side elevation of the delivery 50 end of a flat bed manifolding machine.

Figure 2 is a perspective detail of the resilient pressing and guiding devices to bring the paper down on the pins.

55 Figure 3 is a perspective view of the paper tear-off knife and guide.

Figure 4 is a perspective view of the hooks which hold down the plate shown in Figure 3.

Figure 5 is a perspective view of the paper support and stripper. 60

Figure 6 is a top plan view of the pin mounting and operating mechanism which lies on the bed of the machine beneath the parts shown in Figure 5.

Figure 7 is a detail section of the machine 65 on the line 7-7 of Figure 6.

Figure 8 is an end elevation of the machine with the back plate removed.

Figure 9 is a detail cross section taken 70 vertically through shaft 20.

The machine in the illustration selected for my invention has a frame 1 with a bed 2, on which is a writing table or platen 3. Over this platen, webs of paper 4 of the desired number are passed and copies made 75 by some means such as carbon paper of such notations as are impressed on the top-most web.

In the illustration shown, the bed is hollowed out at the issue end as at 2^a and a U-shaped bar 5 set thereon, said bar being pulled toward the receiving end of the machine by a spring 6 connected to its central lug and lying in a cavity in the bed and having pins 7, 7, set in the ends of its two branching arms and an operating handle 5^a. The movement of the bar is limited by the inner ends of the hollowed out portions of the bed. 80

The bed has lugs 8, 8, at its corners at the issue end of the machine, and in these lugs is pivoted a plate 9, which is slotted at 10, 10, to clear the pins 7 and has a sloping inner edge as at 11. The upper surface of the plate 9 lies on a level with the writing table or platen and the sloping edge is for the purpose of avoiding tearing of carbon paper strips, where same are set close to the issue end of the machine. 85

90 It should be noted that this plate 9 is a continuation of the writing table or platen, and it is disconnected therefrom to simplify the action of the machine. 100

The plate 9 has lugs 12, 12, at its inner end on the inner side of which are mounted the lugs or ears 13, 13, of another plate 14, which serves as a paper guide and tear-off knife. This plate has laterally expanded cams 15 formed beyond the ears 13 and when grasped 105 at the knife end and lifted up, the cams will 110

engage the bed of the machine and lift the free end of the plate 9 upwardly from the bed. Since the paper passes over the plate 9 and under the plate 14, the action will be to 5 lift the paper entirely away from the pins. Stops or hooks 15^a hold the plate 14 from pressing tightly against the paper.

The means for holding the plate 14 down against the paper but without particular 10 friction against the paper is a pair of hooks 16 mounted on a cross shaft 17 beneath the end of the bed, said hooks being pressed by springs 18 into latching position. They engage over pins 16^a extending laterally from 15 the plate 14.

The means for keeping the paper down on the pins and serving as a means for resiliently returning the plate 14 to latched position are a pair of hold down forks 19 on a 20 cross shaft 20, which shaft serves as the pivot for the ears of the plate 14 and is mounted in the lugs on the inner corners of the plate 9.

This shaft has a spring or springs 21 thereon, which tend to force the forks down 25 against the paper, and the ends of the forks are undercut so that the tips will lie at the closing edges of clearance slots 22 in the plate 14, and the balance of the forks will 30 come down to a level with the undersurface of said plate 14 within said clearance slots, the slots of the forks being of a size to straddle the main body of the pins.

Mounted in a pair of housings 23 at one 35 or both sides of the machine are dogs 24 spring-pressed upwardly at 25, which dogs will move into a position to engage behind the cams 15 on the plate 14 when it is raised up.

40 The dogs or the single dog are coupled to arms 26 on a cross shaft 27 beneath the platen or bed, so that a handle 28 fast on this shaft can be employed to positively depress the dogs.

45 As so constructed the operation of the machine is as follows:—The operator brings the desired number of webs of paper over the machine writing table, aligns them, and engages them over the pins, permitting the 50 forks and plate 14 to come down over the paper. He then works to and fro the handle 5^a which moves the pins forward and back, so as to jog the holes of the various webs into true alignment.

55 He then makes the desired impressions on the paper, after which he lifts up the plate 14, first releasing the latches thereof. This lifting may ordinarily be done by merely 60 releasing the latches and pulling upwardly on the paper that protrudes under the plate 14.

Having lifted the plate 14 sufficiently, the dogs will snap behind the cams and the cams by their action will have lifted up the supporting plate 9 and stripped the paper from

the pins. The paper may then be withdrawn for a short distance, and the handle 28 pulled up, which will release the dogs and permit the plate 14 to be moved toward closing position by the spring fork device. 70

The pins will bear against the paper and keep it lifted up somewhat in the clearance spaces of the plate 14, thus keeping the spring forks in the position shown in Figure 1 in dotted lines at 19^a. As soon as the 75 holes in the paper come over the pins as the manual withdrawing of the webs continues, the forks will move clear down, forcing the paper over the pins and moving the plate 14 to latching position.

It should be noted that the plate 9 alongside of its lugs and at the sloping portion 11 is slotted as at 11^a to clear the inner ends of the cams 15 on the plate 14 which engage the bed of the machine to accomplish its lifting 85 operation ahead of the lugs 12.

I have illustrated but one form of mechanism which shows a method of aligning paper by means of pins without providing for resilient motion of the pins. I wish it 90 understood that various equivalent mechanisms known in the manifolding machine art could be substituted for those shown and described, and do not wish my claims to be limited because of failure to mention the said 95 equivalents.

One of the advantages of the forcing of the paper down rather than relying upon pin movement upwardly into the paper from 100 below, is that the operator can see the action of the parts against the paper and regulate the pull on the paper, and need not rely upon the springs alone to make the machine fully effective, since with the hand not occupied with withdrawing the paper, he can 105 press down on the spring forks and plate 14 to take the place of the springs.

When referring to pins in the plural in the following claims it will be understood that this is intended as descriptive, and one 110 pin will, to a lesser degree, serve the same purpose and respond to the same combination.

Having thus described my invention, what I claim as new and desire to secure 115 by Letters Patent, is:—

1. In a manifolding machine, a writing surface upon which a plurality of webs of paper may receive impressions, a paper engaging pin or pins, movably mounted, means for confining the pin or pins for movement lengthwise of the path of withdrawal of the webs and adapted to engage holes in the paper webs and by their movement to jog the holes into line, means for moving the pin or pins and means movable into and out of contact with the paper for pressing it down over the pins, and means for lifting the paper off from the pins, for the purpose described. 120
125
130

2. In a manifolding machine, the combination with aligning pins movably mounted to impart a jogging motion to webs of paper through engagement with holes therein, of a support for the paper through which the pins pass, said support being liftable to strip the paper from the pins.
3. In a manifolding machine, the combination with aligning pins movably mounted to impart a jogging motion to webs of paper through engagement with holes therein, of a support for the paper through which the pins pass, and means for lifting the said support to strip the paper from the pins, and resilient means for pressing the paper against said support.
4. In a manifolding machine, the combination with a paper support, and movable aligning pins protruding through clearance in said support, of means for resiliently holding the paper down against the support, and means for lifting the support to lift the paper from the pins.
5. In a manifolding machine, the combination with a paper support, of aligning pins protruding through clearance in said support, means for moving said pins to impart jogging motion to webs of paper through engagement with holes therein, means for lifting the support to lift the paper from the pins, and resilient means adapted to press against the paper adjacent the location of the pins, whereby the paper may be drawn over the point of protrusion of the pins, and when holes therein arrive at the said point, said resilient means will force the paper down over the pins.
6. In a manifolding machine, a paper support, aligning devices extending through the support, means for lifting the support to disengage the paper from the aligning devices, and means for holding the paper down against the aligning devices, said means being also mounted so as to lift away from the aligning devices.
7. In a manifolding machine, a paper support, aligning devices extending through the support, and means for lifting the support to disengage the paper from the aligning devices.
8. In a manifolding machine, a paper support, aligning devices extending through the support, means for holding paper down against the support, and interconnection between the support and the said means, whereby lifting of said means will lift the support.
9. In a manifolding machine, a paper support, aligning devices extending through the support, means for holding paper down against the support, and interconnection between the support and the said means whereby lifting of said means will lift the support, said last noted means being resiliently held against the support.
10. In a manifolding machine, a paper support, aligning devices extending through the support, means for holding paper down against the support, and interconnection between the support and the said means, whereby lifting of said means will lift the support, said interconnection comprising a pivot for said means on the support, said support being movably secured to the machine at a point removed from said pivot, and abutment devices on the said means to engage a fixed element to lift the pivot point when said means is moved.
11. In a manifolding machine, the combination with a paper support, means for pivoting said support on the machine, clearance in the support, aligning pins extending through the said support, and a tear-off knife pivoted on the support, and cam devices on the tear-off knife to impart a lifting to the knife and hence to the support upon a tilting of the knife.
12. In a manifolding machine, the combination with pins having a short path of movement, means for confining the path of movement to one lengthwise of the path of withdrawal of webs of paper to engage holes in said manifolding paper and jog the paper into alignment through the said movement, means for moving the pin or pins, means for holding the paper down on the pins, and means for lifting the paper off of the pins.
13. In a manifolding machine, the combination with pins having a short path of movement, means for confining the path of movement to one lengthwise of the path of withdrawal of webs of paper to engage holes in said manifolding paper and jog the paper into alignment through the said movement, means for moving the pin or pins, means for holding the paper down on the pins, and means for lifting the paper off of the pins, said holding means being resiliently actuated.
14. In a manifolding machine, the combination with pins having a short path of movement to engage holes in manifolding paper and jog the paper into alignment through the said movement, means for holding the paper down on the pins, and means for lifting the paper off of the pins, said holding means being resiliently actuated, said holding down means comprising two elements, one a plate having clearances located over the pins, and the other, spring fork means straddling the said pin position and resiliently held against the paper.
15. In a manifolding machine, the combination with pins having a short path of movement to engage holes in manifolding paper and jog the paper into alignment through the said movement, means for holding the paper down on the pins, and means for lifting the paper off of the pins, said holding down means being resiliently actuated.

ated, said holding down means comprising two elements, one a plate member having wide clearances located over the pin position, and the other comprising forked means closely straddling the pin position and resiliently held against the paper to force it down over the pins when holes in said paper come into alignment therewith.

16. In a manifolding machine, the combination with aligning pins movably mounted to impart a jogging motion to webs of paper through engagement with holes therein, of a support for the paper through which the pins pass, and means for lifting the said support to strip the paper from the pins, and means for pressing the paper against said support.

17. In a manifolding machine, the combination with a paper support, and movable aligning pins protruding through clearance in said support, of means for holding the paper down against the support, and means for lifting the support to lift the paper from the pins.

18. In a manifolding machine, the combination with a paper support, of aligning pins protruding through clearance in said support, means for moving said pins to impart jogging motion to webs of paper through engagement with holes therein, means for lifting the support to lift the paper from the pins, and means adapted to press against the paper adjacent the location of the pins, whereby the paper may be

drawn over the point of protrusion of the pins, and when holes therein arrive at the said point, said means will force the paper down over the pins.

19. In a manifolding machine, the combination with a paper support, of aligning pin or pins extending across the path of the paper on the support so as to enter holes therein, and means for lifting the support to strip the paper from the pins to permit removal of a length of paper, said means being operable by a lifting of the protruding ends of the paper beyond the pin position.

20. In a manifolding machine, the combination with a paper support, of aligning pin or pins extending across the path of the paper on the support so as to enter holes therein, and means for lifting the support to strip the paper from the pins to permit removal of a length of paper, said means being operable by a lifting of the protruding ends of the paper beyond the pin position, and spring means for resisting the lifting of said means.

21. In a manifolding machine, the combination with an aligning pin or pins, of means for holding paper down resiliently over said pins, whereby it will sink over the pins upon registry of apertures therein with the pins, and means for lifting the holding means away from the pins.

JOHN Q. SHERMAN.
